UNITED STATES PATENT OFFICE.

JOHN FANNING, OF BROOKLYN, N. Y., ASSIGNOR TO FLORENCE L. BURCHARD,
JESSIE L. FANNING, AND ELIDA H. PURDY, OF SAME PLACE.

LEMON-SQUEEZER.

SPECIFICATION forming part of Letters Patent No. 233,339, dated October 19, 1880.

Application filed January 27, 1880.

To all whom it may concern:

Be it known that I, JOHN FANNING, of the city of Brooklyn, in Kings county and State of New York, have invented a certain new and useful Improvement in Lemon-Squeezers, (Case B,) of which the following is a specification.

My invention consists in the combination, in a lemon-squeezer, of a standard, a sector-shaped receptacle secured to the standard by means of a pin passing through lugs upon the standard and receptacle and a presser pivoted in such relation to the receptacle that it may be moved toward the back thereof to squeeze the lemon sidewise, and provided with a handle, whereby it may be operated.

In the accompanying drawings, Figure 1 is a side view of a lemon-squeezer embodying my improvements, showing the arc-shaped receptacle in section, and Fig. 2 is a perspective back view of the receptacle detached, including certain of its appurtenances and fastenings.

Similar letters of reference designate corresponding parts in both figures.

A designates a base-piece, of wood or other suitable material; and B designates a standard, of cast-iron or other appropriate metal, secured thereto, as here shown, by screws *a*.

C designates a sector-shaped receptacle for lemons or half-lemons to be squeezed, open at the front and having an arc-shaped bottom, provided near the back with openings or perforations *b*. The back of this receptacle is bifurcated or recessed at the top, as at *c*, to embrace the upper part of the standard B, bears against a stud, *d*, extending from the standard B, and near the bottom is provided with lugs *e*, which straddle a lug, *f*, extending from the front of the standard, and are fastened thereto by a removable pin, *g*. By removing the pin *g* the receptacle C may be readily detached for cleaning.

D designates a presser consisting of a plate of metal or other material of about the width of the interior of the receptacle C, pivoted to a fulcrum-pin, *h*, in the upper end of the standard B, so that it may be moved forward and backward in the said receptacle. This presser may be operated by means of a lever, E, which, as here shown, may be cast in the same piece with it, and consequently have the same fulcrum.

The fulcrum-pin *h*, to which the presser D is pivoted, is arranged in position forward of the inner wall of the back of the receptacle, and the operating-face of said presser extends radially to said fulcrum-pin or pivot, so that when said presser is brought into a position parallel with the inner wall of said receptacle a sufficient space is left between the operating-face of the presser and said wall for the accommodation of the lemon-rind, and the pressure is applied uniformly to the whole surface of the half-lemon, as indicated in dotted outline in Fig. 1.

Half-lemons are placed with the cut sides downward in the receptacle C, and on the backward movement of the presser D are squeezed sidewise, so that the juice will be forced out from the cut side through the openings or perforations *b* in the bottom of the receptacle.

It will be seen that I thus produce a very cheap and effective lemon-squeezer of remarkable simplicity and little liable to get out of order.

What I claim as my invention, and desire to secure by Letters Patent, is—

The combination of the standard B, the receptacle C, lugs *e* and *f*, and pin *g*, presser D, and lever E.

JOHN FANNING.
